LOCOMOTIVE STOKER

Charles J. Surdy, Tuckahoe, N. Y., assignor to
The Standard Stoker Company, Incorporated,
a corporation of Delaware

Application May 12, 1938, Serial No. 207,465

3 Claims. (Cl. 110—105.6)

This invention relates to locomotive stokers and more particularly to the type which feeds into the firebox through the grate thereof.

It is the principal object of this invention to provide a new and improved arrangement for installing the stoker to locomotives of existing design without the entailment of expensive alterations in the locomotive.

A further object of this invention is to provide a stoker having a fuel elevating conduit which enters the firebox through the plane of the grates and between the side and center grate bearer bars thereof.

It is also an object of this invention to provide a protective grate for the fuel elevating conduit and a new and improved supporting means for the protective grate.

A still further object of this invention is to provide a support for the protective grate, said support being arranged for insertion into the firebox through the firing opening in the backwall thereof.

These and other objects, together with their attendant advantages will become apparent as the following description of the invention is read in connection with the accompanying drawings, in which—

Fig. 1 is a vertical section through adjacent portions of a locomotive and tender, showing the invention partly in section and partly in side elevation;

Fig. 2 is a plan view of the stoker structure shown in Fig. 1 with a portion of the firebox in section;

Fig. 3 is a sectional view from within the firebox taken along the line 3—3 of Fig. 1; and

Fig. 4 is a perspective view of the supporting member for the fuel elevating conduit protective grate.

On these drawings, L indicates a locomotive 40 having a boiler 10 mounted above the frame 11. The boiler 10 comprises a firebox 12 having a backwall 13 provided with a firing opening 14 above the grates 15 and also above the cab deck 16. Rearward of the locomotive L is a tender T 45 connected to the former by the buffer B and including an underframe 17 above which is supported the tank 18. The tank 18 is provided with a fuel bin 19 above the tender deck 20.

Within the firebox 12 and at its lower portion 50 is a center grate bearer bar 21 which extends longitudinally of the firebox along its medial plane. Along a side wall 22, 23, the firebox 12 carries a side bearer bar 24, 25 respectively. The center and side bearer bars 21, 24 and 25 are se-

cured to the firebox in known fashion. Grates 15 are provided with pintles 26 for engaging suitable recesses 27 in the bars 21, 24 and 25, thus affording adequate support for the grates 15.

Heretofore, stokers of the type which fed upwardly through the firebox grate required that a new center grate bearer bar be provided with a "wish bone" effect at one end through which passed the stoker conduit. At each side of the 10 "wish bone" portion of the center grate bearer bar, short grate sections were provided. The provision of a new center grate bearer bar is an expense which is charged to the ultimate cost of a stoker. This expense is eliminated by the provision of a stoker of the following construction.

The stoker S includes a conveyor conduit 30 rigidly mounted on the tender T, a fuel delivery conduit 31 rigidly mounted on the locomotive L and an intermediate conveyor conduit 32 which is 20 flexibly connected at 33 and 34 to the conduits 30 and 31, respectively, by suitable ball joints. Fuel in the bin 19 drops into the conduit 30 and is conveyed forwardly by a system of conveyor screws, one of which is shown at 35 within the intermediate conveyor conduit 32. The foremost end 25 of the conveyor screw 35 projects into the elbow 36 of the delivery conduit 31 and cooperates therewith to force fuel upwardly through the vertical conduit 37, the latter forming the terminal part of the fuel delivery conduit 34. A pressure fluid head 38 is mounted at the upper end of the vertical conduit 37 and issues blasts of pressure fluid against the column of fuel rising through the conduit 37. In this manner, the fuel is projected to all parts of the firebed.

The vertical conduit 37 enters the firebox 12 through the plane of the grates 15 and extends along one side of the center grate bearer bar 21 and adjacent the backwall 13 of the firebox. As shown in Figs. 2 and 3, the vertical conduit 37 enters the firebox 12 through the space between the center bar 21 and the side bar 24, thereby obviating the necessity for installing a new center bar with a central opening or "wish bone" for accommodating the vertical conduit.

Since the vertical conduit 37 is within the firebox 12, means are provided for protecting this part from the extreme heat. This means comprises a lower protective grate section 39 and an upper protective grate section 40, substantially V-shaped in section and arranged to embrace the vertical conduit 37. The upper grate section 40 rests upon the lower section 39 and carries on its upper side a ring-like member 41, the upper surface 42 of which is flush with the upper end of

the vertical conduit 37. Fuel is projected forwardly by the pressure fluid head 38.

Preferably, the protective grate sections 39, 40 and the ring-like member 41 are supported upon a part of the locomotive firebox. For this purpose, an H-shaped support member 9 (Fig. 4) is provided and it includes a pair of parallel bars 43, 44 and a cross bar 45. At each end of the parallel bars 43, 44 is an outwardly extending pintle 46 and it fits into an appropriate recess 27 of the center bar 21 and side bar 24. The upper surface of the support member 9 is flush with the upper surface of the firebox grates 15 when said support member 9 is in operative position. The cross bar 45, together with the parallel bars 43, 44, defines a pair of indentations 49, 50 and also has formed therein a pair of recesses 51 into which grate supporting pintles are fitted, as will presently appear.

In assembling, the H-shaped support member 9 is introduced into the firebox 12 through the firing opening 14 by first inserting one end of a parallel bar 43, 44 into said firing opening and then threading this support member through. This has been satisfactorily demonstrated with firing openings of existing form. Usually, when the support member 9 is inserted into the firebox 12, the vertical conduit 37 is not yet in position and it is thus a very easy matter to place the support member 9 so that each of the four pintles 46 fits into an appropriate recess 27 of the center and side bearer bars 21 and 24. With the support member 9 in position, short grate sections 60 are fitted over the indentation 49. Each short grate section 60 has a pintle 61 on its outer end for fitting into an appropriate recess 27 and 51 of the side bearer bar 24 and cross bar 45, respectively.

After assembly of the firebox grates, the vertical conduit 37 is inserted through the indentation 50 in operative position over the elbow 36. The vertical conduit 37 passes freely through the indentation 50 and the space is closed by the lower protective grate section 39, the latter resting upon the center bearer bar 21 and the bars 43, 44 and 45 of the support member 9. Above the lower protective grate section 39, the upper section 40 and ring-like member 41 are placed in proper sequence.

Since the vertical conduit 37 enters the firebox 12 at one side of its longitudinal medial plane, the fuel distributing head 38 is arranged so as to be at one side of the conduit 37. The jet opening 62 of said distributor head 38 may

also be directed in a manner best calculated to spread the fuel evenly over the firebed.

It will be apparent from the foregoing that a stoker of the underfeed type has been provided which feeds through the firebox grate at one side of the longitudinal plane thereof and in this manner obviates the necessity for providing a new center bearer bar of the "wish bone" type.

I claim:

1. In a firebox, side grate bearer bars and a center grate bearer bar extending straight the full length of said firebox, grates supported by said bearer bars, a removable support member carried by said center bearer bar and a side bearer bar, a stoker for feeding fuel into said firebox comprising a fuel delivery conduit passing through said support member, said fuel delivery conduit being disposed between the center bearer bar and a side bearer bar, and grates along one side of said fuel delivery conduit supported by such side bearer bar and said support member.

2. In a firebox, side grate bearer bars and a center grate bearer bar extending straight the full length of said firebox, grates supported by said bearer bars, a removable support member carried by said center bearer bar and a side bearer bar, a stoker for feeding fuel into said firebox comprising a fuel delivery conduit passing through said support member, said fuel delivery conduit being disposed between the center bearer bar and a side bearer bar, grates along one side of said fuel delivery conduit supported by such side bearer bar and said support member, and a protective grate embracing said fuel delivery member.

3. In a firebox, side grate bearer bars and a center grate bearer bar extending straight the full length of said firebox, grates supported by said bearer bars, a stoker for feeding fuel into said firebox comprising a fuel delivery conduit extending upwardly through the plane of said grates between said center bearer bar and one of said side bearer bars, a removable support member disposed between said conduit and said last named side bearer bar and adjacent said conduit, said support member being carried by said center bearer bar and said side bearer bar, and grates between said conduit and said last named side bearer bar supported by said side bearer bar and said support member.

CHARLES J. SURDY.
